DESIGN FOR A MOLDING

Joseph C. Goss, Detroit, Mich., assignor to J. C. Goss Co., Detroit, Mich., a corporation of Michigan

Application March 29, 1937, Serial No. 68,449

Term of patent 14 years

To all whom it may concern:

Be it known that I, Joseph C. Goss, a citizen of the United States, residing at Detroit, in the county of Wayne and State of Michigan, have invented a new, original, and ornamental Design for Molding, of which the following is a specification, reference being had to the accompanying drawing, forming part thereof.

Figure 1 is a front elevation of a section of the molding;

Figure 2 is a transverse section thereof, and
Figure 3 a view in perspective, showing my new
design.

I claim:

The ornamental design for a molding, as shown.
JOSEPH C. GOSS.
